UNITED STATES PATENT OFFICE.

EDWARD THUNDERBOLT, OF CARLTON, VICTORIA.

GOVERNOR FOR REGULATING SPEED OF MACHINERY.

SPECIFICATION forming part of Letters Patent No. 567,366, dated September 8, 1896.

Application filed July 10, 1896. Serial No. 598,778. (No model.)

To all whom it may concern:

Be it known that I, EDWARD THUNDERBOLT, a subject of the Queen of Great Britain, and a resident of Drummond Street, Carlton, in the Colony of Victoria, Australia, have invented certain new and useful Improvements in Governors for Regulating the Speed of Machinery, of which the following is a specification.

10 This invention has been devised to provide improvements in connection with that class of machinery known as "governors," that is to say, mechanism for regulating the supply of the motive fluid, gas, or electric current to engines and the like or for operating any approved mechanism for controlling or regulating the speed of machinery, and may be described as follows:

15 I employ one or more magnetic coils capable of controlling any desired voltage in electricity, attached and subject to the general circuit of an electric installation. I arrange such electromagnetic coil or coils to operate on the speed-regulating gear of machinery in 20 the most approved manner under the varying circumstances on the different kinds of engines, such as electric-lighting engines, where the speed is so required to be regulated as to increase when the increased number of 25 lights are switched on and, vice versa, to decrease with the reduced switching when lights are being turned off.

30 The magnetic coil is so arranged as to magnetically attract or operate a bar, rod, plate, or lever which is directly or indirectly in engagement with either the motive-power supply or an intermediate mechanism employed for the purpose of controlling the said motive-power supply, such, for instance, as switches 35 of an electric motor, or a throttle-valve of a steam-engine, or gas or oil supply to a gas-engine or the like.

35 In some cases the magnetic coil may operate, as aforesaid, directly or indirectly upon 40 break-gear for reducing the speed of an engine or other machinery.

45 In the accompanying drawings I have illustrated my invention as arranged to control the motive fluid of a steam-engine to work an 50 electric-light supply, and in which—

Figure 1 shows a general view of the apparatus in elevation, a part being shown in sec-

tion. Figs. 2, 3, and 4 show side views of parts of the apparatus.

In the drawings, A represents a lever which 55 has a fulcrum-standard A' arranged to slide at its lower end on a fixed beam B and at its upper end along the lever A. The said lever turns upon the pins A³. The sliding standard A' is secured in the desired position on 60 the lever by means of the thumb-screws A² B². The lever A has adjustably connected thereto a rod C, which is linked to a vertical piston-rod C', carrying a piston C². The rod C has threaded sides and passes through a 65 slotted portion of the lever A, in which a milled screw C³ is set to adjust said rod. The piston C² is arranged to work within a cylinder D. This cylinder D is supported against the wall by a band R and has a number of 70 V-shaped openings D', which form a communication between such cylinder and an outer casing D². The aforesaid piston is arranged to control in its movement the amount of opening from the outer casing D² to the 75 cylinder, and so regulate the inlet of fluid to such cylinder. A pipe is connected to the said casing at E, by which the steam from the boilers is conducted to the casing of cylinder D, while the cylinder has an outlet-pipe F to 80 conduct such fluid to the engine. The lever A has at its side opposite to that at which the fulcrum is placed a magnet-core G, such core being connected to the lever by linked screw-rods G' G² in the adjustable part G³, by which 85 the height of such core may be regulated. The core G is arranged to depend partially into a coil H. Said coil is secured upon a base-plate I, which rests upon a wall-bracket I'. Terminals H' H² are attached to the base- 90 plate to which the circuit-wires are connected. The coil H is provided with a magnetic plug H³ for assisting to attract the core G and which has its distance from the core G adjustably arranged by the thumb-screw H⁴ and screw-pin H⁵, set in the frame H⁶.

A frame J (see Fig. 3) is attached to the fixed beam B and has a slot J', in which the lever A moves vertically, screws J² J³ being provided to limit the travel of the said lever. 100

The lever A has a safety appliance connected therewith, (see Figs 1 and 2,) which will automatically act to cause the piston C to close the ports D', and so stop the flow of

motive fluid and instantly cause the engine or motor to cease running. The attachment consists of a spring K, which is secured to the lever A at one end and to a slotted frame K' at the other end.

- 5 A pin L is arranged to project into this slotted frame and to form a hold on the spring K and lever attached when in its normal working. This pin L has an arm L', by which it is 10 pivoted at L² to a plate M, the plate M with the attachment L' being adjustably raised or lowered by the pin M' and thumb-screws M² on the fixed wall-bracket O. A vertical rod N is adjustably secured to the lever A and 15 is arranged to engage with the projecting end of the pin L, its distance from such end being adjustable by the milled nut N'.

The *modus operandi* of the invention may be described as follows: Assume the appliance to be connected up with the inlet-pipe E connected to the source of fluid supply and the pipe F controlling the engine. If the apparatus be at work and an additional number of lights be switched onto the circuit, it will 20 immediately cause a decreased current to pass through the coil H, and consequently a less attractive force will be exerted on the core G, thus allowing the spring K to act to raise such core partially out of the coil, which 25 action will raise one end of the lever A and with it the piston-rod C and piston attached, thus opening the V-shaped ports D' in the cylinder D and allowing an inrush of steam or other motive fluid into the cylinder and 30 through the pipe F to the engine. The speed of the engine will thereby be increased, so communicating to the dynamo an increased speed and consequent increase of electrical supply to maintain a greater number of lights 35 on the circuit. In shutting off a number of lights a reverse action will take place, that is, the core G will be drawn down and with it the lever A, so lowering the piston C² and proportionately closing the ports D'. If the

current be suddenly cut off from the circuit, 45 the safety appliance will come into operation, so as to prevent the racing away of the engine. The pull of the core G will then be relaxed and the spring K will cause same to jump up and with it the rod N, secured to the 50 lever A, so causing said rod N to strike the pin L and cause it to turn on its center L², thus releasing its opposite end from engagement with the slotted frame K', which, now released, drops and with it the end of lever A, 55 so causing the piston C², connected to the lever, to close the ports D' and thus stop the further supply of fluid to the engine.

Having now particularly described and ascertained the nature of my said invention and in what manner the same is to be performed, I declare that what I claim is—

1. In governors for regulating the speed of machinery—the combination of an electromagnet as G, H adjustably secured to a lever 65 A having a sliding fulerum-standard as A' with a piston-rod as C, C' adjustably secured to such lever and carrying a piston as C² which operates to open and close ports as D' in a cylinder as D such cylinder having an 70 outer casing as D² with inlet and outlet pipes as E and F substantially as and for the purposes set forth.

2. In governors for regulating the speed of machinery—the combination of a lever as A 75 having a spring as K attached thereto at one end and at the other end to a slotted frame as K' in combination with a pin as L, L' centered upon an adjustable plate as M and a vertical rod as N adjustably connected with 80 the lever A substantially as and for the purposes set forth.

Signed this 18th day of May, 1896.

EDWARD THUNDERBOLT.
